METHOD OF MAKING A RUG FRINGE

Clarence F. Arnold, Drexel Hill, Pa.

Application August 3, 1936, Serial No. 93,963

2 Claims. (Cl. 66—193)

This invention has to do with the making of a rug fringe, and is concerned primarily with the method of making the rug fringe illustrated and described in the copending application of 5 Arnold, Serial Number 75,918, filed April 23, 1936, issued as Patent No. 2,102,934, the present application being a continuation in part of the said copending application of Arnold.

The present invention has in view, as an important objective, the provision of a method for 10 making a decorative fringe that is characterized by the presence of a relatively large diameter base cord and which base cord carries the fringe strands of small diameter as compared to the 15 base cord.

In providing a method of making a fringe of this type, an important feature is the inclusion of a step of moving the thin fringe strand to form a series of loops, the bends of which overlie the 20 base cord, and then stitching the bends to the base cord by passing a thread back and forth through the base cord, which thread interlocks with the bends of the fringe strand.

Another object of the invention is the provision of a method in which a pair of large diameter base cords are arranged in spaced relationship, and a fringe strand of smaller diameter is moved to form a series of loops, the bends of 25 which overlie the base cords. The bends are then stitched to the base cords by passing a connecting thread back and forth through the base cord and interlocking the thread with the bends of the fringe strand. The loops of the fringe strand are then divided along a line intermediate 30 the base cords.

The present invention has in view as an objective the provision of a method of making rug fringe which involves the use of the ordinary flat knitting machine in a novel manner, to carry 40 out the steps of the present invention.

The rug fringe which is manufactured by the present method includes a base cord to which are anchored the fringe strands. In accordance with the present invention a pair of base cords are fed past the needles of a flat knitting machine in a fixed spaced relationship. A strand of the material which is to make up the fringe in the finished product is then passed back and forth from one base cord to the other, and as this strand reaches each base cord it is stitched thereto by proper operations of the needles of the flat knitting machine.

After the material in this condition has passed 55 from the knitting machine, it is divided along a

line intermediate the base cords, to provide two strips of rug fringe.

A particular feature of the present invention is the manner in which the fringe strand is anchored to the base cord. By availing of a spring 5 beard knitting needle, the material of the base cord may be effectively pierced to securely stitch the fringe strand thereto.

At the same time a latch needle may be employed in conjunction with the spring beard needle, but at a point just off the base cord. Such latch needles are effective to provide a row of 10 stitches across the turns of the fringe strand along the line of joinder with the base cord, thus providing good reinforcing effects.

Various other more detailed objects and advantages will in part become apparent, and in part be hereinafter stated, as the description of 15 the invention proceeds.

The invention, therefore, comprises the method 20 of making a rug fringe on a flat knitting machine, and which includes the steps of arranging a pair of large diameter base cords in spaced relationship, passing a fringe strand of smaller diameter back and forth between the base cords to form 25 a series of loops, having bends overlying the base cords, stitching and interlocking the bends of the fringe strand to the base cords by passing connecting threads back and forth through the base cords, and forming lines of reinforcing stitches 30 adjacent to the base cords by interlocking reinforcing threads about the fringe strands.

After the base cords and the fringe strand, which has been stitched thereto, pass from the knitting machine, it is divided along a line intermediate 35 the base cords, to provide two strips of the rug fringe.

For a full and more complete understanding of the invention, reference may be had to the following description and accompanying drawing, 40 wherein:

Figure 1 is a plan view, somewhat diagrammatic, bringing out the manner in which the base cords and fringe strand are fed past the needles of a flat knitting machine,

Figure 2 is a view similar to Figure 1, bringing out the movement of the tube which carries the fringe strand, and

Figure 3 is another similar showing, bringing out the arrangement after several turns of the 50 fringe strand have been anchored to the base cords.

Referring now to the drawing, wherein like reference characters denote corresponding parts, the dotted line at 10 is intended to indicate the 55

line of needles on an ordinary flat knitting machine. Inasmuch as these flat knitting machines are well-known in the textile arts, it is not thought necessary to herein present an illustration of the same, as those skilled in the textile arts are familiar with their construction and mode of operation.

5 A stationary tube is shown at 11, and another stationary tube is indicated at 12. These tubes 10 are in a fixed spaced relationship, and are intended to constitute a feed for the base cords represented at 13 and 14, respectively.

As the latter are fed past the line of needles, represented at 10, another tube, shown at 15, is 15 movable back and forth between the base cords 13 and 14. This tube 15 constitutes a feed for a fringe strand, shown at 16.

As shown in Figure 2, the strand 16 is anchored to the base cord 13 by two rows of stitches, designated 17 and 18 respectively. The stitches 17 20 are formed by spring beard needles, which have the ability to pierce the base cord 13 and securely anchor the turn of the fringe strand 16 thereto.

At the same time the stitches 18 are formed 25 by latch needles which operate between the turns of the strand 16. After the strand 16 has been anchored to the base cord 13, as shown in Figure 2, the tube 15 moves in the direction indicated by the arrow, over to the base cord 14, where a 30 similar stitching operation takes place, after which the tube 15 is again returned to the base cord 13.

This cycle of operation is repeated to provide 35 the product illustrated in Figure 3, the formation of the fringe being a more or less continuous operation carried out by the flat knitting machine. When the material in the condition shown in Figure 3 is taken from the knitting machine,

it may be divided along the line indicated at 19, to provide two strips of rug fringe of the character clearly set forth in the said copending application.

While a preferred specific embodiment of the 5 invention is hereinbefore set forth, it is to be clearly understood that I am not to be limited to the exact steps illustrated and described, because various modifications of these details may be provided in putting the invention into practice 10 within the purview of the appended claims.

I claim:

1. The method of making a decorative fringe which consists in arranging a pair of relatively large diameter base cords in spaced relationship, passing a fringe strand having a small diameter as compared to the base cords back and forth between the base cords to form a series of loops having bends of the fringe strand overlying the base cords, stitching and interlocking the said 20 bends of the fringe strand to the base cords by passing connecting threads back and forth through the respective base cords and dividing the loops of the fringe strands along a line intermediate the base cords. 25

2. The method of making a fringe which consists in arranging a relatively large diameter base cord in close proximity to a fringe strand of smaller diameter, moving the said fringe strand to form a series of loops having bends overlying 30 the base cord, stitching and interlocking the said bends of the fringe strand to the base cord by passing a connecting thread back and forth through the base cord and forming a line of reinforcing stitches adjacent to the base cord by 35 interlocking a reinforcing thread about the fringe strand. 30
